CABLE OPERATED SIDE-LINE DITCHING
MACHINE OF THE BOOM TYPE

Luke B. Babin, White Castle, La.

Application November 29, 1946, Serial No. 712,827

1. Claim. (Cl. 37—116)

1

The present invention relates to improvements in combination ditch digging and cane loading machines and has for an object to provide an improved machine convertible for use either for digging ditches or for loading cane.

Another object of the invention is to provide a ditcher and loader that may be converted from one to the other by the mere interchanging of the ditching bucket and the cane loader grab. This is made possible because the machine is designed to perform both operations in the same manner.

A further object of the invention is to provide a ditching and cane loading machine employing a swinging boom with operating connections thereto which automatically function to swing the boom in the one, and sequentially in the opposite direction, by the simple act of tensioning the cables of the operating mechanism and then slackening one of the cables to incidentally utilize the weight of the implement to restore the boom.

With the foregoing and other objects in view, the invention will be more fully described hereinafter and more particularly pointed out in the appended claim.

In the drawings, in which like parts are denoted by the same reference characters throughout the several views,

Figure 1 is a side elevation of one form of the device constructed in accordance with the present invention and being shown as employed for ditch digging operations.

Figure 2 is a fragmentary top plan view of the present invention showing the ditching bucket engaged in the loading operation.

Figure 3 is a vertical section taken on the line 3—3 in Figure 2 and showing a form of windlass-clutch mechanism on an enlarged scale.

Figure 4 is a fragmentary side elevation of the device, constructed according to the present invention as employed in the cane loading operation, illustrated with the grab in one phase of its lifting position.

Figure 5 is a side elevation of one form of ditching bucket as used in connection with the present invention and taken on an enlarged scale.

Figure 6 is an end elevation of Figure 5 taken from the left-hand end.

Figure 7 is a side elevation of the ditching bucket and its suspending means hoisted and in a dumping position.

Figure 8 is a side elevation of the cane grab in the raised and dumping position.

Figure 9 is an end elevation of a form of brake adjusting device.

2

Referring more particularly to the drawings, 10 designates a self-propelled mobile crane with rear wheels 11 on axes at right angles to the vehicle and driven from a power unit 12 through a conventional transmission and differential 13 and having front wheels 14 on conventional spindles for steering.

A boom 15 is mounted for universal swinging movement on the vehicle frame at the rear thereof and off the center line of same. The boom 15 may be carried by a horizontally rotating turntable 56 to which the boom 15 is connected by pivots 57 having substantially horizontal axes. A main mast 16 is erected on the turntable 56 coincident with the vertical axis of the turntable. Diagonal braces 17 and 18 extend from the vehicle body and converge angularly to the upper end portion of the mast 16, the mast having a rotary bearing in the upper end of such braces.

20 The boom 15 has horizontal swinging movement about the vertical axis of the turntable, and such boom 15 has vertically adjustable movement about the pivots 57. In respect of its vertically-adjusting motion it may be retained in any desired position by the adjustment of a cable 26 and a chain 35 by locking the chain 35 in a chain retaining plate 37, which is affixed to the main mast 16 at the top thereof.

An outrigger 19 is mounted to the right side of the vehicle 10 and carries an adjustable sheave 20 through which passes a cable 27. The sheave 20 is adjusted horizontally toward and from the vehicle in order to reach over the ditch in the ditch digging operation so that the bucket 40 may be pulled by the cable 27 along the center line of the ditch. The inner end of the cable passes over a sheave 22 on the vehicle by which such cable is directed to a windlass drum 24. The other end of the cable forms part of a closed loop involving the upper and lower cable runs 27^a and 27^b and a chain or other flexible connection 46. The cable runs 27^a and 27^b are rove through a sheave 21 swung from the outer end of a companion cable 28. The near ends of the lower runs 27^b and 46 of the loop are connected together to a forward part of a bar 38 pivoted to a beam 50 attached to the bucket 40. The far end of the chain 46 is affixed to the cable 27 by a connecting piece or clamp 53.

40 A windlass drum 25 carries and has affixed to it one end of the cable 28. The run of the cable 28 is defined by passing over sheave 23, which is horizontally mounted to the vehicular frame 10, over a sheave 39, which is horizontally mounted 45 to the left rear of the vehicular frame 10, and

50 55 to the left rear of the vehicular frame 10, and

thence over a sheave 41, carried on the boom 15 approximately midway of the length of said boom, and finally over a sheave 42, carried on the free end of said boom 15. The free end of the cable 28 is affixed to the eye 43 of a swivelled sheave carrier 44 in which the sheave 21 is rotatably mounted.

The ditching bucket 40 is supported by two chains 36, the upper ends of which are affixed to the sheave carrier 44, the lower ends being affixed rearwardly of the center of gravity of the ditching bucket 40 by means of engaging eyes 45 on the bucket 40. A beam 50 of the nature of a plow beam is connected to the rear end portion of the bucket 40 and projects to a substantial extent forward of the bucket and forwardly of the digging point or edge 52. One or more bars 38 are pivoted as at 63 to the beam 50 at a considerable distance back from its forward end where the beam carries an upstanding perforated or other adjusting strap or straps 64 to which the bar 38 may be pinned in any adjustment about the fulcrum 63. It will be noted from Figure 6 that the side walls of the bucket 40 flare or diverge upwardly. As shown in Figure 1 the proximate ends of the lower loop runs 27^b and 46 are connected to the outer free end of the bar 38.

The windlass drums 24 and 25 are carried freely on a power shaft 47 which carries spline 48, over which laterally floats clutching gears 49 and 49^a having teeth 30 and 30^a which engage sockets 31 and 31^a respectively, on the sides of the windlass drums 25 and 24. Yokes 29 and 29^a are arranged to slide gears 49 and 49^a into mesh with drums 25 and 24 respectively. Braking drums 32 and 33 are attached to and carried by windlass drums 24 and 25 respectively. Brake bands 34 pass over the brake drums 32 and 33 to maintain them in the stopped or tension position when so desired. As shown in Figure 9 brake band pressure may be applied by any suitable device. For instance, one end of the brake band 34 is anchored at 59 while the other end is coupled to a lever 60 pivoted at 61 to a bracket 61^a and secured in an adjusted position by a ratchet latch 62. The bracket 61^a is secured to the frame of the vehicle 10 in any suitable manner and at any desired location so that the lever 60 will be accessible to the operator of the device.

In operation the invention functions as follows:

The sheave 20 is placed over the center line of the ditch to be excavated and the vehicle 10 is in position to travel parallel to the ditch. The digging cycle commences with the ditching bucket 40 resting upon the earth to be excavated. The clutch yoke 29^a moves clutching gear 49^a toward the windlass drum 24 such that teeth 30^a on the clutching gear 49^a engage the sockets 31^a on the sides of the windlass drum 24 and impart rotation thereto. Meanwhile, the windlass drum 25 remains idle on the power shaft 47. The cable 27 passing through the sheave 20 draws the chain 46 taut thus dragging the ditching bucket 40 along the bottom of the proposed ditch. When the ditching bucket 40 is full, the clutching gear 49^a is disengaged from the windlass drum 24 and the brake is applied to the brake drum 32 to maintain tension on the cable 27.

The clutch yoke 29 is then moved laterally along the spline 48 to engage the teeth 30 of the clutching gear 49 into the sockets 31 in the side of the windlass drum 25 and thus impart rota-

tion thereto; this causes the winding in of the cable 28 thus raising the point of the rigid draw bar 50 by putting tension on the chain 46 and cable 27^a and 27^b. This causes the point 52 of the ditching bucket 40 to raise first as best seen in Figure 1. The cable 28 is continued to be wound upon the windlass drum 25 and thus causes the entire bucket to raise. After the ditching bucket 40 has been lifted clear of the ditch, the cable 28 continues to be wound upon the windlass drum 25 and thus causes tension in the hook-up between the sheaves 20 and 42, thus causing the boom 15 to swing in the direction of the outrigger 19. During the swinging movement of the boom 15 towards the outrigger, the bucket 40 acts as a part of the connection between the cables 27 and 28. When the boom 15 has swung sufficiently to place the ditching bucket 40 over a spoil bank, the brake on the windlass drum 24 is then released and the clutch disengaged from the windlass drum 25 and the brake applied to the brake drum 33 thus releasing tension on the cables 27, 27^a, 27^b and chain 46 allowing the nose or point 52 of the ditching bucket 40 to drop. The dirt is thus dumped from the ditching bucket 40 to the spoil bank as best seen in Figure 7.

The end portion of the cable 28 which is attached to the drum 25 is fixed against movement since the brake is set on the drum 25 and the digging bucket 40 which is of substantial weight exerts a pulling force on the free end portion of the cable 28 sufficient to create an angular pull between the sheaves 20 and 42 to cause the boom 15 to swing away from the outrigger 19. It will be noted that during the movements of the boom 15 both towards and away from the outrigger 19 the cable 28 and the bucket 40 serve as part of the means for such movement: the cable 27 coacting with the cable 28 and the bucket to move the boom towards the outrigger and the bucket 40 coacting with the cable 28 in lieu of the cable 27 to move the boom away from the outrigger. When the ditching bucket 40 is directly over the ditch due to the swinging of the boom 15, the brake on the windlass drum 25 is released thus dropping the ditching bucket 40 into the ditch. The cycle is then recommenced.

The aforesaid device as described in connection with ditch digging may also be very readily adapted to be used as a cane loading device merely by the substitution of a cane grab which will be hereinafter described more fully. This is possible because the machine is designed to perform both operations in the same manner.

The cane grab 53 is shaped like a horizontal U with an automatic trigger 54 pivoted at 65 on the front or working end of the grab 53 such that when tension is brought upon the cables 27^a and 27^b the trigger 54 will be actuated to the closed position and retain the cane loaded therein.

When the grab 53 is resting upon the ground prior to loading, the trigger 54 is held in the open position by means of a coil spring 55 and the grab 54 sweeps the heap row and is loaded with cane. The grab 53 is drawn along the heap row by the cable 27. When the grab is fully loaded with cane and it is desired to place the cane in a cane receiving cart or vehicle (not shown), the grab is raised in a manner similar to that of the ditching bucket 40 at which time the cables 27^a and 27^b actuate the trigger 54 to close the open end of the grab 53 and thus retain the cane therein. The grab 53 is swung

over the cane receiving cart similar to the manner in which the ditching bucket 40 is swung over the spoil pile and is then dumped by the slackening of the cable 27 thus causing the trigger 54 to assume the open position because of the action of the coil spring 55 and permitting the cane to fall from the grab 53. This dumping position may best be viewed in Figure 8.

The use of this invention in the field of digging and cane loading provides:

A small, light mobile machine, primarily designed for the small farmers, the size of whose operations would not economically permit the use of standard equipment.

A bucket and cane grab which is light enough so that one man can change the implements by himself.

An outrigger with adjustable sheave which permits the machine to be used close to a ditch or a heap row or a distance therefrom, permitting use of best travelling lane for the machine.

A plow beam with adjustable straps on front end that regulates the angle of draw cable pull for the digging bucket so that the desired digging depth can be attained.

Since the boom is swung from its loading to unloading positions by an angle pull of the hoist line and the draw line the usual boom swinging mechanisms are eliminated and simplifies the operation by doing away with the operating levers and uses no extra power from the power unit.

It will be understood that the "loop" referred to in the claim is comprised of the upper run 27^a and the lower run composed of the two legs 27^b and 46. For convenience, in that embodiment of the invention illustrated in the drawings, the upper run 27^a and the lower run leg 27^b are shown as continuations of the hauling cable 27 but whether or not these members 27^a and 27^b are integral with the hauling cable 27 is of no moment as the hauling cable 27 may be regarded as attached at its outer end to the forward end 58 of the loop. The critical feature resides in the fact that it is a loop and that the lower run of the loop at its intermediate portion is connected to the beam which projects forwardly from the material container 40 or 53 as the case may be.

While I have disclosed herein the best form of the invention known to me at the present time, I desire it to be understood that I reserve the right to make changes and modifications in the herein described embodiment of the invention provided such changes fall within the scope of the following claim.

What I claim is:

In a machine for the purposes described, a vehicle, an outrigger projecting laterally from said vehicle, a boom mounted on said vehicle for lateral swinging movement, a hauling cable, a wind-

lass on the vehicle on which one end of the cable is wound, an outrigger pulley mounted upon the outrigger over which the hauling cable is passed and directed away from the outrigger in a line substantially parallel with the line of movement of the vehicle and spaced laterally therefrom, a loop connected at one of its ends to the other end of said hauling cable at the end of such parallel line, a loop pulley supporting the opposite end of the loop through which the opposite end of the loop is rove, a lifting cable having an outer end connected to and carrying said loop pulley, a boom pulley on the outer end portion of said boom over which said lifting cable is passed, a second windlass on the vehicle on which the inner end portion of said lifting cable is wound, a material container, a container support supported and carried from the outer end portion of said lifting cable and having a lower end pivotally connected to the container rearwardly of center of gravity to bias the container to a dumping position, a beam extending forwardly of the container and of said support and coupled to the lower run of said loop whereby when the hauling cable is slack the eccentric weight of the container and its load will pull down upon the lower slackened loop causing dumping and when the hauling cable is put under pulling tension the lower run of the loop will be pulled into substantially straight line position thus rotating the container about its support to an erect position, a bar pivoted to the beam to couple the beam to the lower run of said loop, said bar having a forward end which is at a considerable distance forward of the pivot point, a rigid adjusting strap extending upwardly from the forward end portion of said beam and means affixing said bar to the strap in various angular positions of said bar.

LUKE B. BABIN.
